(57) **CLAIM**

The ornamental design for a cycling shorts pad, as shown and described.

DESCRIPTION

FIG. 1 is a front, right side perspective view of a cycling shorts pad showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The broken lines in the drawings and the areas within broken lines illustrate portions of the cycling shorts pad that form no part of the claimed design.
